(57) **CLAIM**

The ornamental design for a cartridge for water purifier, as shown and described.

DESCRIPTION

FIG. 1 is a perspective view of a cartridge for water purifier showing our new design;

FIG. 2 is another perspective view thereof;

FIG. 3 is a front view thereof, the rear view being a mirror image of the front view;

FIG. 4 is a left side view thereof;

FIG. 5 is a right side view thereof;

FIG. 6 is a top view thereof;

FIG. 7 is a bottom view thereof; and,

FIG. 8 is a reference view thereof shown with the two filtration units in the separated state.

The broken line showing in FIG. 8 forms no part of the claimed design.
